UNITED STATES PATENT OFFICE

165,151

COMBINATION TOY BANK AND SHOE TREES

Jules Golden, Bronxville, N. Y.

Application January 19, 1951, Serial No. 13,881

Term of patent 7 years

(Cl. D34—11)

To all whom it may concern:

Be it known that I, Jules Golden, a citizen of the United States, residing at Bronxville, in the county of Westchester and State of New York, have invented a new, original, and ornamental Design for a Combination Toy Bank and Shoe Trees, of which the following is a specification, reference being had to the accompanying drawing, forming part thereof.

In the drawing:

Fig. 1 is a perspective view of a combination toy bank and shoe trees, showing my new design.

Fig. 2 is a front elevational view of the same in which the shoe trees are shown bent forwardly.

Fig. 3 is a rear elevational view of the combination toy bank and shoe trees shown in Fig. 1.

Fig. 4 is a side elevational view of the same.

Fig. 5 is a side elevational view of the combination toy bank and shoe trees shown in Fig. 2.

I claim:

The ornamental design for a combination toy bank and shoe trees, as shown.

JULES GOLDEN.
